UNITED STATES PATENT OFFICE.

ANDREAS HANSEN, OF CUMBERLAND MILLS, MAINE.

WIRE-STRETCHER.

1,353,835.

Specification of Letters Patent. Patented Sept. 28, 1920.

Application filed August 27, 1917. Serial No. 188,321.

To all whom it may concern:

Be it known that I, ANDREAS HANSEN, a citizen of the United States, residing at Cumberland Mills, in the county of Cumberland and State of Maine, have invented certain new and useful Improvements in Wire-Stretchers, of which the following is a specification.

This invention relates to improvements in wire stretchers of the type employed for straightening wire fences and its prime object is to produce a device of this class that is simple in construction, durable and efficient in operation. With the foregoing and other objects in view the invention consists in the combination and arrangement of parts to be hereinafter fully described, pointed out in the appended claim and illustrated in the accompanying drawings which form a part of this specification and in which—

Figure 1 is a side elevation of my improved device illustrating its application.

Fig. 2 is a top plan view of the device, on an enlarged scale.

Like reference characters denote corresponding parts throughout the several views.

In stretching the wires of a wire fence I provide an anchor post 1 and a core 2, the core being a metal or wood member of cylindrical shape which is formed near each end with annular grooves 3. Threaded wire rods 4 terminating in eyes 5 that engage with the grooved portions 3 of the core 2 are connected by turnbuckles 6 with similar threaded rods 7 that engage the said anchor post. I provide a hand lever 8 formed with an offset 9 and terminating at one end in an eye 10 and provided with spaced collars 11, 11 at its opposite end and between said collars a sleeve 12 is pivotally arranged upon said lever, said sleeve being formed

with a finger 13 in which a hook 14 is formed for engagement, normally, with one strand 45 of fence-wire 15. Should the wire 15 become slack it is stretched by first driving the anchor post 1 into the ground in advance of the end fence post 16, the core 2 being then disposed between that post and the 50 said anchor post. The fence wires are then drawn beyond the fence post 16 and coiled, once or twice, about the core 2 and then secured to the eye-forming end 10 of the lever 8. The said lever 8 is then rotated 55 about the core in a direction to wind the fence wire upon the core until all slack is taken out of the wire and the finger 13 and hook 14 of the lever are then placed in engagement with one of the wire strands to 60 retain the lever in adjusted position. Should the anchor post lean toward the core 2 at its upper end the core may be adjusted to suit by means of the turnbuckles 6.

What is claimed is:—

In a wire stretcher, the combination with an anchor post, a rotary core, means adjustably connecting said rotary core to said anchor post, a hand lever having an offset portion associated with said core and terminating in an enlarged eye to receive the ends of the wire to be stretched, said hand lever being adapted to be rotated about said core, and having a bearing thereupon meanwhile adjacent the offset, whereby said wire 70 is wound upon said core, a sleeve pivotally carried upon said hand lever, and a wire-engaging finger carried by said sleeve.

In testimony that I claim the foregoing as my own I have hereto affixed my signature in the presence of two subscribing witnesses.

ANDREAS HANSEN.
